BOWLING SCORE SHEET FILM POSITIONING AND HOLDING DEVICE

Stanley E. Condon, Plymouth, Ohio, assignor to American Machine & Foundry Company, a corporation of New Jersey

Filed Aug. 27, 1964, Ser. No. 392,562
9 Claims. (Cl. 88—24)

This invention relates generally to a device for positioning and holding a bowling score sheet on the transparent or translucent writing table of a conventional bowling score projector. More particularly, this invention relates to such a score sheet holding device for use especially during team play, which includes a magazine for storing a supply of unused score sheets and which is relatively easy to remove from and replace on the writing table with the score sheet in proper aligned position with the projecting system of the score projector.

At present, with conventional bowling score projectors, it is common practice to utilize a heavy-gauge, costly, transparent printed sheet having from one to six scoring areas thereon to provide for temporarily recording a bowling score which is to be displayed by a bowling score projector so that the various scores are visible to an audience watching the bowlers. Due to the cost of such heavy-gauge printed sheet, it is common practice to make a record of the score and then erase the markings from the heavy-gauge printed sheet so that the sheet can be reused. Since there is frequently no reproducing device available at the bowling alley for making a permanent record from the heavy-gauge score sheet, it is necessary to manually transfer the scores for various frames to a separate, inexpensive sheet after play is completed. The inconvenience of transferring the scores and the cost of erasing and handling such reusable sheets has been found to be very undesirable.

Another undesirable aspect of such heavy-gauge, reusable sheets is the removal and replacement of the sheets after each team game. The heavy-gauge reusable sheets are only used during team play. When the lanes where the bowling score projector is located are used by other bowlers, an inexpensive score sheet is provided. Hence, there is normally no provision on the writing table of the projector for properly aligning the heavy-gauge sheets relative to the projecting system of the projector. Therefore, each time a heavy-gauge sheet is replaced, during team play, it is necessary for the scorekeeper to look at the projected image to determine that the sheet is properly positioned to display the score for view by the audience. If the sheet is not properly positioned, the game is frequently delayed, with corresponding inconvenience to the team players, and increased expense to the bowling alley proprietor, since the bowlers pay on a per-game basis.

This invention alleviates, during team play, the problems previously encountered with heavy-gauge, reusable printed score sheets by providing a score sheet holder and positioning device which includes a magazine for storing a plurality of score sheets in the form of thin, transparent film. In the preferred embodiment, yet to be disclosed, the frame of the score sheet holder functions to accurately position the score sheet, or score sheets, as the case may be, relative to the projecting system of the score projector when the score sheet holder is mounted on the writing table in a predetermined position. A magazine for storing unused score sheet film is secured to the frame. Hence, when team play commences it is merely necessary for the proprietor of the bowling alley to provide the teams with a holder which can be easily carried to and mounted on the writing table of the projector. After

2

team play is completed, the score sheet holder is returned to the proprietor and normal, inexpensive score sheets can again be used by non-team players on the writing table of the projector, since it is not necessary to project the scores of non-team players.

In accordance with one embodiment of this invention, the score sheet itself is a clear, transparent sheet of film material with no printing thereon to indicate the various player lines or frames. In this instance, a printed score grid is connected to the frame of the score sheet holder and it is merely necessary to pull the clear film into position over the printed score grid. In a variation of this concept, the score grid may be permanently associated with the transparent or translucent writing table of the projector, such as by etching or otherwise permanently affixing the score grid to the writing table. The score sheet grid may also be directly printed onto the score sheet film in the conventional manner.

Another distinct advantage of the score sheet, score sheet holder and frame of this invention is the disposition of score sheets in side by side relation on the same scoring table to permit one scorekeeper to record the scores of two opposing teams.

Accordingly, an object of this invention is to provide a bowling score sheet holder which is effective to accurately position a score sheet film in proper aligned registration with the projecting system of a bowling score projector.

Another object of this invention is a bowling score sheet holder which includes a magazine for storing unused score sheet film.

Another object is a holder for score sheet film which maintains the scoring surface of the film exposed for writing thereon by a score keeper, and in which the positioning frame of the holder is secured to a score sheet magazine to provide a one-piece unit that is easily removed and replaced.

A further object of this invention is a holder for score sheet film in a continuous strip, which film is manually fed from a magazine to proper position on the writing table of a bowling score projector and which includes a device for severing used score sheet film from the unused film.

Yet another object is a combined bowling score film holder and magazine with its various parts so arranged that the score sheets of opposing teams are maintained in side-by-side relation on top of the same writing table of the score projector to permit one scorekeeper to record the scores of two opposing teams, and in which the holder is positioned in the normal ashtray slots of the writing table of the score projector and the ashtrays themselves function to secure the holder to the score projector table.

Another and further object is a combined film holder and magazine which includes a securing device to hold score sheet film fed from the magazine in a predetermined position and against accidental movement.

A still further object is a bowling score film holder and magazine which is inexpensive to manufacture, easy to use, and provides for the use of relatively inexpensive transparent film for recording a permanent record of the team games as played.

In order that the manner in which the foregoing and other objects are attained in accordance with the invention can be understood in detail, particularly advantageous embodiments of the invention will be described with reference to the accompanying drawings, which form a part of this specification, and wherein:

FIGURE 1 shows a bowling score projector system on which the score sheet holder of this invention is mounted in use;

FIGURE 2 is a perspective view of the score sheet

holder mounted on the writing table of the bowling score projector of FIGURE 1;

FIGURE 3 is a plan view showing the mounting of the score sheet holder on the writing table of the projecting system;

FIGURE 4 is a view in side elevation of the score sheet holder and magazine;

FIGURE 5 is a view in section looking along lines 5-5 of FIGURE 3;

FIGURE 6 is a view in section looking along lines 6-6 of FIGURE 3;

FIGURE 7 is a view in section looking along lines 7-7 of FIGURE 3;

FIGURE 8 is a partial view in plan of a transparent preprinted score sheet film in position in the holder;

FIGURE 9 is a view similar to FIGURE 8 with a transparent unprinted score sheet film in position in the holder, the score sheet grid being permanently associated with the glass of the projector table;

FIGURE 10 is a view similar to FIGURE 8 with a transparent unprinted score sheet in position in the holder, the score sheet grid being on a transparent sheet disposed between the score sheet film and the projector table glass; and

FIGURE 11 is an enlarged sectional view looking along lines 11-11 of FIGURE 10.

Referring now to the drawings in detail, and particularly to FIGURES 1 and 2, a score sheet holder and positioning device 1, in accordance with this invention, is shown mounted on the writing table 2 of a bowling alley scoring projector 3.

Scoring projector 3 is of the general type disclosed in U.S. Patent 2,330,799 Coker and, as best seen in FIGURE 1, includes a pedestal 4 on which writing table 2 is mounted, and a housing 5 spaced above writing table 2 and supported by a suitable bracket 6, the housing 5 containing a suitable mirror and lens system to project the image written upon score sheet film 7 disposed on table 2 onto a screen 7' due to the action of light projected upwardly through the score sheet from a projecting lamp within pedestal 4.

As shown in FIGURE 2, writing table 2 of the scoring projector includes a transparent or translucent glass plate 8 disposed between portions 9 and 10 which may be of wood covered with a durable material such as Formica.

As best seen in FIGURES 3 and 4, score sheet holder 1 includes a frame 11, and a score sheet film magazine 12 connected to one side of the frame and disposed below the plane of the frame.

Frame 11 includes a body member 13 of thin sheet metal, an elongated edge strip 14 also of sheet metal and secured to the upper face of the body portion adjacent its top edge as by welding, and a spring biased score sheet film retainer 15 disposed midway of the body portion and which functions to prevent movement of the score film 7 by pressing same against a plate secured to the frame, as shown in FIGURE 6. At one side of the score sheet retainer 15, body portion 13 is cut away to provide an elongated, generally rectangular opening 16. A similar opening 17 is provided in body portion 13 on the other side of score sheet retainer 15.

Although each of openings 16 and 17 appears to be generally rectangular as seen in FIGURES 3 and 8-10 a careful observation shows that the inner side edges 18 of openings 16, 17 are somewhat longer than the outer side edges 19 of these openings. Due to this difference in length the bottom edges 20 of each opening slope upwardly in a direction away from the center of score sheet holder 1. Such convergence of bottom edges 20 in a direction toward the side edges of writing table 2 serves two functions. The first is that such an arrangement is more aesthetically pleasing than if openings 16, 17 are truly rectangular. The second is that making the openings converge in a direction toward the edges of the table tends to compensate for the optical and project-

ing system of scoring projector 3. Otherwise, the image projected onto screen 7' would not be truly rectangular, but would be shorter at the center and longer at each side edge of the image unless of course, a complicated optical system is incorporated in the scoring projector to compensate for the difference in distance between the center and sides of the various portions of each score sheet from the lens system in housing 5. As will subsequently be explained in detail, the various score sheet grids of FIGURES 8-10 have laterally extending player lines which also converge slightly in a direction toward the side edges of writing table 2.

Sheet metal of body portion 13 is bent downwardly at the left hand side thereof as viewed in FIGURES 3 and 4 to provide a leg 21, and is then bent outwardly to provide a leg 22 disposed below and offset to one side of body portion 13. The bend 23 between body portion 13 and leg 21 is at a slight angle with the side edges of body portion 13. Bend 24 between legs 21 and 22 is so formed that the plane of leg 22 is disposed at an acute angle to the plane of body portion 13, and these planes intersect in a direction toward an observer looking at the embodiment of FIGURE 4.

Leg 22 provides a mounting support for magazine 12. Magazine 12 includes a first end plate 25 and a second end plate 26, each of the end plates being of sheet metal. The upper edge of each end plate has a flange 27, the flanges being bent inwardly to provide material for welding end plates 25, 26 to the lower surface of leg 22 of score sheet film holder 1. Each end plate 22 is made of thin sheet metal with elastic properties and is provided with a small circular opening 28 generally centrally thereof to receive the reduced diameter ends of a shaft 29 that extends between the end plates. The thin material of the end plates provides sufficient elasticity to permit removing the shaft to renew a roll 30 of score sheet film 7. Mounted in suitable openings offset toward one side of end plates 25, 26 in a direction toward frame 11 is a guide roller 31 which functions to guide film 7 during feeding into frame 11.

As best seen in FIGURES 4 and 5, the side edges of body portion 13 of the holder are turned downwardly and then inwardly to provide a pair of inwardly facing elongated parallel guide slots 32 and 33, the guide slots functioning to receive the edges of the score sheet film while feeding the film into position relative to the projecting system of scoring projector.

Secured to a center web 34 of body portion 13, as by welding, are a pair of spaced apart one-half hinge members 35. A coacting half hinge member 36 is mounted on the upwardly extending portion 37 of score sheet film retainer 15. Suitable torsion springs 38 disposed on a pin 39 which connects the hinge half members together provide the necessary bias to normally press a resilient rubber pad 40 downwardly against score film 7. Since pad 40 is mounted on the underside of elongated flat portion 41 of retainer 15, the pad is normally biased downwardly to clamp score sheet film 7 against a plate 42 secured to frame 11. Upwardly extending portion 37 of the retainer is disposed at an angle to flat portion 41 to provide a convenient hand-engaging surface to lift pad 40 by pivoting flat portion 41 when it is desired to feed additional film. Plate 42 has a width slightly less than web 34 so it is completely hidden from view, and extends only about one half the height of frame 11 to facilitate threading the score sheet film.

Secured to the side of body portion 13 remote from magazine 12 is a flat side plate 43 having an elongated upwardly projecting embossment 44 extending beside end web 45 of frame 11. As best visualized by referring to FIGURES 1, 3 and 7 embossment 44 functions to lift the end edge of film 7 fed through guide slots 32 and 33, when the film is moved to the right as seen in FIGURE 3. It is to be noted that end web 45 of the frame is slightly beveled (FIGURE 7) to provide a sharp cutting

edge 46 to facilitate cutting of the film by pulling the film upwardly when it is desired to separate used film from unused film in the holder.

As best seen in FIGURE 1, writing table 2 is normally slanted in a direction toward the person who keeps score during team play. If the axis of shaft 29 which supports film roll 30 were parallel with the plane of body portion 13, the axis of the roll would normally be disposed at an angle to the horizontal. Such supporting of roll 30 at an angle has been found undesirable because the edges of the thin score sheet film 7 frequently catch on the inlet edges of guide slots 32, 33 with corresponding tearing of the film while feeding. However, it is to be noted with particularity that the axis of shaft 29 is disposed at an acute angle to the plane of frame 11 so that shaft 29 is horizontal when the film holder is mounted on the slanted table of the scoring projector.

With reference to FIGURE 3, it can be seen that writing table 2 is provided with conventional generally rectangular U-shaped recesses 47 and 48 to normally accommodate ashtrays 49 and 50, for the convenience of the bowlers. The film holder of this invention is mounted on the table by first removing the ashtrays, whereupon the holder is positioned so that rear edges 51, 52 of end plates 25, 26 engage the inner center wall 53 of recess 47 and the end edge of side plate 43 projects under ashtray 50. When so disposed, the film holder is maintained in position against accidental movement by the person keeping score, as well as others who may accidentally touch score sheet holder 1.

With reference to FIGURES 3 and 4 it is apparent that score sheet film holder 1 when mounted on writing table 2 has the under-surface of the material which forms the bottom wall of slots 32 and 33 in engagement with the upper surface of glass plate 8. Since the sheet metal of frame 11 is relatively thin, and since the score sheet film 7 is also very thin and flexible, the portion of the score sheet exposed at openings 16, 17 normally rests against the upper surface of glass plate 8 to permit writing on the score sheet with a pencil or other marking instrument used by the scorekeeper. It is to be noted that the height of score sheet holder 1 is slightly less than the height of glass plate 8 to leave exposed marginal edge portions of the glass plate when the score sheet holder is in position. The score sheet holder is so arranged when in position, that openings 16 and 17 are disposed an equal distance from the center of glass plate 8. Since the center line of the optical system of housing 5 is normal to center web 34, it is apparent that inner edges 18 of the frame material which defines openings 16, 17 are each the same distance from the optical system contained in housing 5. Likewise, outer side edges 19 are each the same distance from the optical system in the housing 5.

With reference to FIGURE 8, there is shown one embodiment of score sheet film 7 used with the holder of this invention. In this embodiment the score sheet 7 has printed or otherwise applied thereto a bowling scoring grid 54 comprised of a plurality of generally horizontal lines 55-60 commonly referred to as player lines, and a plurality of vertical lines 61 which define the various frames of a bowling game. It is to be noted with particularity that player line 55 adjacent the top of the exposed portion of score sheet film is parallel with top edge 62 of both openings 16 and 17. However, player line 60 adjacent the bottom of the exposed portion of score sheet film 7 is parallel with bottom edge 20 of only opening 16. The arrangement is such that the various player lines of a proper score sheet disposed in openings 16, if extended beyond the right hand side edge of the table meet at a point which lies on line 55 extended. Likewise, a proper score sheet disposed in opening 17 (not shown) has its player lines so arranged that if extended to the left these player lines also meet at a point lying along player line 55.

This slight convergence of the player lines in a direction away from center web 34 alleviates the need for a truly aplanatic projection system, since the slight distortion at the sides of the image projected onto screen 7' is compensated for by such convergence. As previously stated such an arrangement is also more aesthetically pleasing than a truly rectangular grid where a pair of score sheets are in side by side slightly spaced relation.

In the embodiment of FIGURE 9 the score sheet film is different from that of FIGURE 8. In this embodiment the score sheet film is clear transparent film that is wholly blank. Here, a bowling scoring grid 63 identical to grid 54 is permanently associated with glass plate 8 for example, by etching the grid onto the under-surface of 15 the glass, or by otherwise printing or affixing such a grid on the glass. The grid 63 for each of the teams is disposed in such a position on the glass that it is immediately beneath the respective openings 16 and 17 when holder 1 is mounted on the table. The advantage of this 20 arrangement is that unprinted readily available score sheet film can be used in place of the more expensive preprinted film shown in FIGURE 8.

FIGURES 10 and 11 show another variation relating to the use of a clear unprinted score sheet film. Here 25 the bowling scoring grid 64 is on a transparent grid sheet 65 interposed between score sheet film 7 and glass plate 8 of the projector. Although transparent sheet 65 may be applied directly to the top surface of the glass and temporarily secured thereto for example, with an adhesive, it is preferred to dimension the transparent sheet 30 to fit into guide slots 32 and 33 and to temporarily secure the transparent sheet to the film holder. Then, during play, it is merely necessary to feed the clear unprinted score sheet film across transparent sheet 65 until its appropriate faces are positioned in openings 16 35 and 17, and scoring may then be done by a scorekeeper using the indicia printed on the transparent sheet as a guide. As shown in FIGURE 11 sheet 65 is sufficiently flexible to engage the upper surface of glass plate 8 and 40 thus provide a support for score sheet film 7 when a score is written on its surface.

When non-team bowlers are using the facilities of the 45 bowling alley where the scoring projector 3 is located there is no need to project the various scores of the players for view by an audience. Hence, a normal inexpensive opaque paper bowling score sheet is placed on writing table 2 in any desired position. However, during play a transparent score sheet such as score sheet film 7 is necessary to properly project the scores of the 50 various teams for view by an audience. The proprietor of the bowling alley provides each team with a score sheet holder 1 with the magazine of the holder containing a roll 30 of score sheet film. It is merely necessary for a member of the team to remove ashtrays 49 and 50, 55 place score sheet holder 1 in position on the table with magazine 12 extending into recess 47, and then replace the ashtrays to mount the score sheet holder on the writing table 2. The scorekeeper can then write the appropriate names of the players of the various teams in the 60 spaces defined by the bowling scoring grid. At the end of a game it is merely necessary for the scorekeeper to press down on portion 37 of film retainer 15 to lift pad 40 away from the score sheet film. While pad 40 is lifted the score sheet film is manually fed slightly to the right 65 as viewed in FIGURE 3 whereupon embossment 44 lifts the side edge of the film so that it can be grasped by the scorekeeper. The used portion of the film is then pulled to the right as shown in FIGURE 2 until unused film is 70 properly positioned in the openings 16 and 17. Pressure on portion 37 is then released to again cause pad 40 to clamp the score sheet film between the pad and center plate 42. The used portion of the score sheet is then severed from the web of score sheets by pulling upwardly 75 to sever the film against cutting edge 46. As is apparent

with reference to FIGURES 3 and 4 a roll 30 comprised of a continuous strip of score sheet film is normally stored in magazine 12. The film is fed between guide roller 31 and the inner surface of leg 21 and then into guide slots 32 and 33. With the score sheet holder positioned on the scoring projector, the film engages wall 53 of recess 47 during feeding of the film. Wall 53 functions as a guide to elevate the film to the approximate level of guide slots 32 and 33.

In each of the several embodiments the score sheet film is a transparent, synthetic resinous film for example, regenerated cellulose film, polyethylene terephthalate, polyvinylidene chloride, or cellulose acetate of uniform thickness of 2 to 5 mils (.002 to .005 inch). With some types of film the surface on which the score is to be written must be specially treated, in a well known manner to adapt the surface to receive writing. However, a special pencil or pen may be used which will permit writing on the surface of the film without such surface treatment.

Although a preferred embodiment of the score sheet film holder has been shown and described with a particular bowling scorer projector, and although several preferred types of score sheet film have also been shown and described, it is to be understood that numerous variations and changes can be made without departing from the scope of this invention as defined in the appended claims.

What is claimed is:

1. A score sheet holding device attachable to a bowling score projector table of the type having a top provided with a writing area through which light passes to permit projecting the score from a transparent score sheet for view by an audience, comprising in combination:

a score sheet holder comprising:

an elongated substantially flat frame having an opening therein, and

score sheet guide means connected to said frame; means for mounting said holder on a score projector table with said frame adjacent to and extending across the top thereof;

said opening of said frame element being effective to expose the upper surface of a transparent bowling score sheet to be disposed adjacent said frame and the score projector top, and on which upper surface the score is to be recorded; and

a magazine associated with said frame and adjacent thereto, to store a roll supply of connected unused score sheets and from which a score sheet can be fed to said frame and positioned above said writing area for entries of scores thereon;

said score sheet guide means being effective to facilitate proper positioning of a score sheet relative to said opening of said frame element.

2. A score sheet holding device in accordance with claim 1 including:

means connecting said magazine to said score sheet holder for support thereby when said score sheet holder is mounted on said bowling score projector table.

3. A score sheet holding device in accordance with claim 1 in which:

said last-named means support said magazine below the plane of the top of said bowling score projector table, and means disposing said magazine inwardly of the side edges thereof when said holder is mounted on the projector top;

whereby said magazine is hidden from view and is protected from damage by bowlers in the area of the projector.

4. A system for facilitating bowling scorekeeping and projecting of the recorded score during team play comprising in combination:

a bowling score projecting device having a writing

5.

effective to automatically align said first and second openings with the projection system of said projectors; and
said frame is adapted to receive a pair of score sheets connected together in side-by-side relation. 5
